PACKAGING CONTAINER FOR DAIRY PRODUCTS OR THE LIKE

Edmund C. Iwanski, 5362 N. Nottingham Ave.,
Chicago 21, Ill.

Filed Mar. 17, 1964, Ser. No. 79,040

Term of patent 14 years

(Cl. D58—2)

FIG. 1 is a perspective view of a packaging container for dairy products or the like showing my design.

FIG. 2 is an end elevational view of same.

FIG. 3 is a side elevational view of same.

FIG. 4 is a view taken on lines 4—4 of FIG. 3.

FIG. 5 is a view taken on lines 5—5 of FIG. 3.

FIG. 6 is a sectional view taken on lines 6—6 of FIG. 5, and

FIG. 7 is a sectional view taken on lines 7—7 of FIG. 1.

I claim:

The ornamental design for a packaging container for dairy products or the like, as shown.
